APPARATUS FOR CURLING HAIR

Stephen F. Kayn, New York, and Daniel D. Whyte,
Brooklyn, N. Y.

Application October 26, 1937, Serial No. 171,005

3 Claims. (Cl. 132—31)

This invention relates to improvements in apparatus for curling hair.

Generally, this invention involves the application of a mandrel assembly incorporating a sleeve upon which hair is to be "croquignole" wound, the thus curled hair being maintained on the sleeve as a support after removal of the mandrel assembly.

Specifically, it is an object of this invention to provide for curling hair through the application of a curler assembly incorporating a mandrel member and a tubular curl support applied as a sleeve thereto, such curl support being in the nature of a resilient self-supporting member colored substantially the same as the hair, the mandrel member being operable to wind hair in "croquignole" fashion on the curl support and to be removable from the support after the wound hair has been fastened to the support.

These and other advantages, capabilities and features of the invention will appear from the subjoined detailed description of one specific embodiment thereof illustrated in the accompanying drawing, in which—

Figure 1 is a perspective view of the sleeve element applied in this invention.

Figure 2 is a perspective view of the sleeve and mandrel assembly applied in the invention.

Figure 3 is a perspective view of the sleeve and mandrel assembly at the completion of the curl winding step.

Figure 4 is a perspective view of the sleeve after fastening of the curl and removal of the mandrel.

Referring to the reference characters in the drawing, M represents a mandrel comprising a tubular element 10 having a diameter gradually decreasing from end to end, and at the end of which there is mounted pivot pin 11, on the ends of which is carried clamping arm 12 having curvilinear contour corresponding to that of the tubular element, there being mounted on the pivot pin 11 a coil spring connected to the clamping arm and serving to maintain the same against the tubular element.

Upon the tubular element 10 there is adapted to be disposed tubular coil support 14 in the nature of a sleeve formed of resilient material colored substantially the same as natural hair, but having a greater firmness or body, as, for example, horse hair, or impregnated and stiffened cellulosic or like threads, woven in tubular formation.

Interiorly and extending longitudinally of sleeve 14 there is disposed as by adhesion or stitching

fastening element 15 of bendable material, such as coated wire or the like, the free ends 16 and 17 of which are adapted to rest against the "croquignole" wound hair carried on the sleeve, as shown at 18, to clamp the windings onto the sleeve, the fastening element being likewise colored to substantially conform to the natural hair color.

In operation, the support or sleeve 14 is placed upon the tubular member 10 of the mandrel with the fastening element 15 distant from the clamping arm 12 of the mandrel; the free ends of the strands of hair desired to be curled are firmly disposed against the sleeve 14 and maintained in such position by the pressure of clamping arm 12 under control of compression spring 13.

The mandrel assembly is then rotated with the hair being wound towards its roots, in the flat so-called "croquignole" winding method until the proper curl formation is attained; at this point the free ends 16 and 17 of the fastening element 15 are bent over against the curl 18, such free ends being substantially in parallelism to the support or sleeve 14 and forming a firm clamp for the hair.

After fastening of the formed curl 18 to the tubular support 14, the mandrel assembly 10 is withdrawn from the sleeve by displacing the same in the direction of the arrow, shown in Figure 3.

The tubular support or sleeve having a greater degree of firmness than the hair, forms a definite support for the same and being of color substantially similar to that of the hair, is relatively indistinguishable, thereby permitting the same to be worn or maintained on the head for considerable time.

Although a mandrel of particular type has been disclosed, and a tubular curl support or sleeve woven of horse hair or the like has been described, it is within the province of this invention to apply various types of mandrels or sleeve formed of other and different material according to the method involved for the purpose specified.

It is obvious that various changes and modifications may be made to the details of construction without departing from the general spirit of the invention as set forth in the appended claims.

We claim:

1. In a curl forming apparatus, a mandrel and a resilient sleeve mounted on the mandrel, means on said mandrel for clamping to the mandrel, the sleeve and free ends of hair to be wound on the sleeve flexible hair fastening means mounted interiorly of the sleeve, extending through the open ends thereof and having its free ends bendable

in parallelism with said sleeve for locking the hair wound on the sleeve, said mandrel and clamping means being removable from said sleeve and said sleeve being self-supporting.

5. 2. A device of the class described, comprising in combination, a tubular woven self-supporting curling element, a fastening element mounted interiorly and extending longitudinally of said curling element, having end portions extending 10 through the open ends of the curling element and bendable towards one another into parallelism exteriorly of said curling element, and a curling winder insertable into said curling element and having a clamping member pivotally mounted 15 thereon for gripping the exterior wall of said curling element.

3. In a device of the class described, comprising

in combination, a resilient self-supporting sleeve, a hair fastening element carried on said sleeve and having its free ends extending beyond the ends of said sleeve, the said free ends of the fastening element being bendable into parallelism 5 exteriorly of the sleeve, and a winder member insertable into said sleeve and having a jaw for gripping the exterior of the sleeve, said gripping jaw serving to clamp a strand of hair against the sleeve, said winder member serving to impart 10 rotational movement to the sleeve to form a curl thereon, and the free ends of said fastening element serving to clamp the formed curl onto said sleeve.
